UNITED STATES PATENT OFFICE

96,650

DESIGN FOR A LAMP BASE

Frederick David Chapman, Evanston, Ill., assignor to Montgomery Ward & Co., Incorporated, Chicago, Ill., a corporation of Illinois

Application November 8, 1934, Serial No. 53,937

Term of patent 3½ years

To all whom it may concern:

Be it known that I, Frederick David Chapman, a citizen of the United States, residing at Evanston, in the county of Cook and State of Illinois, have invented a new, original, and ornamental Design for Lamp Base, of which the following is a specification, reference being had to the accompanying drawing, forming a part thereof.

In the drawing the figure is a perspective view of a lamp base showing my new design, the latter being the same at all sides of the lamp base.

I claim:

The ornamental design for a lamp base, as shown and described.

FREDERICK DAVID CHAPMAN.
